UNITED STATES PATENT OFFICE.

ANTONIO DI STASIO, OF NEW YORK, N. Y.

RADIO CONTROL MECHANISM.

Application filed November 30, 1926. Serial No. 151,752.

This invention relates to means for controlling and operating radio apparatus, particularly receiving sets and the apparatus contained therein and adapted to centralize a plurality of normally independent operable means for control by single mechanism.

The invention comprehends the provision of a unitary manually operable control means having a plurality of movements, each of which is utilized for independent control of predetermined parts of a radio set in order that the filament and loud speaker or other reproducer circuits may be independently controlled in a desired manner with the simultaneous operation of the tuning adjustment for the tuning of the circuit or set in the usual manner.

The invention further comprehends the provision of a structure of the above mentioned character which is substantially simple, efficient in operation, and which may be manufactured at a relatively small cost.

The invention comprehends numerous other objects residing in the details of construction, and arrangement of the parts which are more particularly pointed out in the following detailed description and in the claims directed to a preferred form of the construction, it being understood however, that various changes in the size, shape and relation of the parts may be made without departing from the spirit or scope of the invention as herein set forth.

In the drawings forming part of this application:—

Figure 1 is a front elevation of a portion of a radio set showing the operating knob and indicating dial used in conjunction with the operation of the present invention.

Fig. 2 is a vertical longitudinal section taken approximately on the line 2—2 of Fig. 1, showing the mechanism forming the subject matter of the present invention in side elevation and omitting the showing of conventional structure of the set.

Fig. 3 is a horizontal sectional view taken on line 3—3 of Fig. 2.

Fig. 4 is a perspective of the mounting and supporting bracket for the major parts of the mechanism of this invention.

Fig. 5 is an enlarged detail plan view of the movable switch block showing details of construction in dotted lines.

Fig. 6 is a rear elevation on a reduced scale of the switch block indicating the wir-

ing connections between the several terminals and switch plugs carried thereby.

Fig. 7 is a detail taken substantially on the line 7—7 of Fig. 2, showing more particularly the construction of the operating pinions for the tuning apparatus.

1 indicates the panel of a radio set to which is secured the usual base board 2 on which all of the instruments and apparatus comprised in a receiving circuit are usually mounted. A supporting shaft 3 is rotatably mounted at the forward end in the panel 1 and suitably mounted in any desired manner at the rear end thereof, preferably on the base board, not illustrated, which is adapted to mount a gang condenser or combined condensers and inductances movable for tuning cooperation in a plurality of radio receiving circuits, which are generally indicated by the dot and dash lines in Figs. 2 at 4.

This provides a single supporting shaft for all tuning elements of a receiving set. However, any other method of simultaneously operating all of a movable tuning element of a receiving set may be employed instead of a single supporting shaft as shown, and which is merely for the purpose of illustration. The forward end of the shaft is provided with an indicating pointer 5 which cooperates with the scale 6 on the front face of the panel 1 to indicate the tuning adjustments of the instruments carried or operated by said shaft 3.

The rear end portion of the shaft 3 is provided with an enlarged annular gear 7 rigidly secured thereto with which meshes the driving pinion 8 having cylindrical projections 9 from opposite sides thereof rotatably in the parallel arms 10 extending upwardly from the main supporting bracket 11. The arms 10 are at the rear end of the supporting bracket 11 while the forward end thereof extends and is provided with a lateral extension 12 which is secured to the panel 1 by a bushing 13 in turn forming a bearing for rotatably mounting the operating shaft 14 which is provided with a squared portion at its opposite end as indicated at 15 extending through a squared opening formed in the pinion structure and the cylindrical projection thereof as indicated at 16 in Fig. 7.

Adjacent the squared portion 15 and inwardly toward the central portion thereof the operating shaft 14 is provided with a

2

plurality of annular grooves 17 with which 5 which have their free ends adapted for cooperation with the annular grooves 17 as clearly illustrated in Fig. 2 in order to retain the operating shaft 14 in any one of a plurality of positions of slidable adjustment relative to the drive pinion.

A stop collar 19 is secured to the operating shaft or rod 14 for limiting the sliding movement thereof through the bushings 13, while the operating knob 20 on the free end of the 15 shaft in front of the panel, provides a suitable means by which the shaft may be manually rotated or moved axially through the bushings in order to have the resilient fingers 18 seated in the desired recess 17 in the shaft.

20 A movable switch block 21 constructed of suitable insulating material is formed to receive in its upper portion the operating shaft 14 to permit relative rotation of said shaft in the block while the longitudinal or 25 axial movement of the shaft is adapted to move the block therewith through the cooperation of the collars 22 with the opposite ends of said block. The lower portion of the block 21 is slidably received between the 30 upwardly extending flanges 23 formed on the opposite side of the supporting bracket.

11. One of the flanges 23 is formed with a 35 projection 24 to which is secured a suitable insulating block 25 carrying a resilient contact 26 having the tendency to move toward the insulating block 21 for engagement with the contact bars 27 embedded in the face of said block or movable switch block.

40 Suitable terminal posts 28 extend through the opposite end portions of the insulating bars 27 and serve to retain the same in recesses in the movable switch block, and to provide means for receiving electric circuit connections for the contact bars. Terminal posts 29 are also mounted in the movable switch block adjacent the posts 28 for receiving other circuit connections of a desired character.

50 Terminal jacks are mounted in and project from opposite ends of the movable switch block as indicated at 30, particularly in Fig. 5, which include a shell electrode 31 and a center electrode 32 suitably insulated in a manner well known in the art in the construction of the usual plug jacks or phone jacks, and which construction is preferably used for the jacks illustrated. Guide sleeves 33 are secured in the upstanding ears 34 formed beyond opposite ends of the movable switch block 21 for receiving and guiding the jacks 30, while beyond these ears 34 are mounted suitable single circuits, double circuits, or filament control jack operated contact units as illustrated substantially dia- 60 grammatically at 35 and 36 respectively,

which are suitably secured and insulated from supports 11, in such position that the jacks 30 when in a predetermined position, will engage and operate the contacts in a predetermined manner well known in the 70 art.

The types of assemblies for the contact structures 35 and 36 are of any desired type well known in the art such as are used for output control circuits receiving the jack 75 from a usual loud speaker terminal, or any of the numerous types of filaments and B battery control jacks which automatically control the output circuits of a receiving set.

The units 35 and 36 are so arranged on the 80 supporting bracket 11 as illustrated in Fig. 2, that only one jack cooperates with one of the units at a time, while in a desired position, the jacks are positioned, so that the circuits of both units are in the normal position 85 ready for operation by either jack. The three annular grooves 17 in the operating shaft are positioned in such relation that the central groove is the position of the block member 21 when the jacks are in the central 90 position, and the units 35 and 36 are not operated thereby, while the other grooves represent the positions of operation of the respective jacks for the respective units 35 and 36 depending upon the position of the 95 operating shaft 14.

In operation, the resilient contact member 26 engages the bar contact 27 when the block member is at either of its opposite limits of movement, while in the central position, the 100 resilient contact 26 engages between said bar contacts, and circuits controlled thereby are open in said central position.

A suitable insulating block 38 supports the rear end of the bracket 11 on the base 105 board 2. With a construction such as illustrated in the drawings and above described, it will be readily understood that circuit connections for the A battery as well as the B battery and loud speaker terminal may be 110 controlled by the units 35 and 36 in cooperation with the jacks 30 in the movement of the movable switch block 21, and with the further cooperation of the bar contacts 27 and the resilient contact 26. This control- 115 120 125 operation is affected through the actual movement of the operating shaft 14 by pulling the knob out or pushing it in, so that the resilient fingers 18 cooperate with the desired annular groove 17 in the shaft, while an off position is provided with the resilient fingers 18 in the central annular groove 17.

In this way, a multitube receiving circuit may be controlled to interpose a loud speaker or other reproducer in circuit with the detector tube or in circuit with all of the tubes of the set including audio frequency amplifying tubes according to the position of the movable switch block 21 in controlling the jack units 35 and 36 and the

circuits between the resilient contact 26 and bar contact 27. Any predetermined wiring connections may be made to obtain the desired type of control.

5 In addition, the rotation of the shaft 14 operating the drive pinion 8 and the spur gears 7 tunes the entire set and provides a single tuning control for a radio receiving set in addition to the circuit control features 10 above referred to.

It will therefore be clearly understood that the present invention provides a unitary control member having a series of independent movements adapted for use in affecting 15 the control of a plurality of independent elements in a radio receiving set in order to centralize all of the controls of a receiving set into a single control.

Having thus described my invention, what 20 I claim as new is:—

1. A uni-control for radio receiving sets, wherein the receiving set includes a plurality of movable tuning elements, comprising operated means carried by said elements, movable 25 able to produce adjustments thereof, driving means for said operated means, a plurality of circuit control units, movable means for operating said circuit control units, and a single manually operable mechanism associated with said means and said driving 30 means adapted to independently operate each of said means in a predetermined manner.

2. A uni-control for radio receiving sets, 25 wherein the radio receiving set includes a plurality of independently movable instru-

ments having driven means for simultaneously moving said instruments, driving means for operating said driven means, a supporting member operably mounting said driving 40 means, a plurality of circuit control units carried by the supporting member in spaced relation, slideable means for operating said circuit control units carried by the supporting means, and a main operating control 45 carried by the supporting means and associated with the slideable means and the driving means and independently operable in a plurality of directions for selectively operating said driving means and sliding means. 50

3. A uni-control for radio receiving sets, wherein the receiving set includes a plurality of independently movable instruments, comprising driven means carried by said instruments, a supporting bracket, driving means 55 mounted in said supporting bracket and operably connected with said driven means for simultaneously operating the same, a plurality of circuit control units mounted on said supporting bracket, a block member 60 slideable on said supporting bracket, an operating shaft rotatably and slideably mounted in said supporting bracket, and operably associated with the driving means and the slideable block member whereby axial 65 movement of the shaft in the supporting bracket will operate said block member and rotatable movement of said operating means will operate the driving means.

In testimony whereof I affix my signature. 70

ANTONIO DI STASIO.
